DISPLAY CONTAINER

John T. Hartnett, Boston, Mass.

Application August 5, 1937, Serial No. 157,557

8 Claims. (Cl. 206—44)

This invention relates to boxes, cartons, and similar containers of those types in which small merchandise, such as tacks, toilet soap, and other articles, are shipped to the retailer. For convenience such containers will be hereinafter referred to generically as "boxes".

The invention aims to devise a box of this character which, in addition to performing the usual functions of a box, can also be used as a support or easel for holding the base of the box and its contents on a store counter, or the like, in such a position as to display the goods in an attractive manner.

The nature of the invention will be readily understood from the following description when read in connection with the accompanying drawings, and the novel features will be particularly pointed out in the appended claims.

In the drawings,

Figure 1 is a perspective view of a box embodying this invention;

Fig. 2 is a similar view of the cover of said box;

Fig. 3 is a perspective view of the box shown in Figs. 1 and 2 and illustrates the manner in which it may be used to display merchandise;

Fig. 4 is a vertical, sectional view of a slightly different form of box embodying this invention;

Fig. 5 is a plan view of the box shown in Fig. 5 in its original or closed condition;

Figs. 6 and 7 are views similar to Figs. 5 and 4, respectively, showing a further modification;

Fig. 8 is an angular view of still another embodiment of the invention; and

Fig. 9 is a vertical, sectional view showing the manner in which the box illustrated in Fig. 8 may be used.

Referring first to Figs. 1, 2 and 3, the box there shown is made of cardboard, or other equivalent sheet material, and includes a base 2 and a cover 3. These parts may be made by any suitable method. The top of the cover, however, is cut, scored, perforated, or weakened in any other suitable manner, along the lines indicated at *a* to divide the section of the cover between the lines of scoring *b* and *c* into two parts indicated at 4 and 5, respectively. The lines of cut *a* are so made that the very small portions of the cover between adjacent cuts serve to hold the entire cover top in the same plane during the shipment of the goods and their delivery to the retailer. These uncut portions, however, can readily be broken simply by pressing upon them, and the sections 4 and 5 can then be bent downwardly between the lateral walls of the cover into the inclined positions illustrated in Figs. 2 and 3.

When the retailer wishes to display the goods, he removes the cover 3 from the base 2, folds the parts 4 and 5 down, as shown in Figs. 2 and 3, and then places the base 2 with its contents into the seat thus formed for it in the cover, as illustrated in the latter figure. It will be observed that in this arrangement the two parts 4 and 5 are disposed in an inclined relationship to each other, and also at an angle to the plane of the top of the cover, where they form a V-shaped seat, the section 4 supporting the bottom of the base 2, while the part 5 bears against and supports the lower end of the box.

Thus the base of the box with its contents may be supported, without the use of parts additional to those essential to the construction of the box, in such a position as to display the goods in an attractive manner.

A display card 6 may also be used to cover the small boxes 7 containing the tacks or other merchandise packed in the base 2, this cover forming a false top and lying under and reinforcing the weakened portion of the top of the cover. When the box is opened and set up for display purposes, the lower end of this card may be slipped into the top of the base between the end and the boxes, as shown in Fig. 3, or it may be supported in slots cut in the upper end of the base 2, this card bearing advertising matter or display features of any suitable character.

If the box is longer in proportion to its width, or is heavily loaded, it is preferable to support it at a somewhat lower angle, as shown in Fig. 4, and the sections 4 and 5 are cut accordingly. In this construction, as in that above described, the cutting is so done as to form a tongue *d* on the section 5 which enters a notch in the other section, and this tongue may be scored, as shown at *e*, to provide an end tab *f* which is folded under the lower corner *g*, Fig. 4, of the base 2. Thus this extension of the section 5 underlies the lowermost corner of the base and avoids any possibility of the base sliding under the cover, in the event that the load which it carries tends to produce this result.

The embodiment of the invention illustrated in Figs. 6 and 7 is like that shown in Figs. 1, 2 and 3 except that a lip 8 is cut out of the material of the section 5 where it projects over the upper edge of that end of the base 2 which is located in the seat formed by the parts 4 and 5 and thus assists in supporting the base in its inclined position.

Still another form of the invention is shown in Figs. 8 and 9. Here the cover 10 is scored and

cut to provide sections 11 and 12, respectively, one cut from the top and the other from a lateral wall of the cover. The scoring is indicated by the lines 13, 14 and 15. Thus these parts 11 and 5 12 can be bent downwardly, as shown in Fig. 9, to provide a V-shaped seat for the base 16 of the box.

In all of these forms of the invention use is made of only that material which necessarily goes into the construction of the box, no additional parts being required to produce the results here described. It will be understood, also, that the proportions of the parts 4 and 5 will necessarily be determined by the angle at which it is desired to support the base and to some degree, also, by the weight of the merchandise carried by the base. An important advantage of the invention is that when supporting the merchandise for display purposes the box does not occupy a greater area of a counter or showcase than does the box itself when in its closed condition, except in such forms as those shown in Figs. 4 and 9, and even here the added area of the counter required is so slight as to be immaterial. 25

It should also be noted that in these various forms of the invention the angles of inclination which the inclined portions of the cover take when supporting the base in its display position, depend upon the depth of the cover, the lower 30 corner of the base resting upon the counter, table, or other support on which the cover is mounted, or else upon the portion of the cover immediately underlying said edge of the base, and which itself is resting on the table or counter. Thus a solid support for a heavily loaded box is provided.

Having thus described my invention, what I desire to claim as new is:

1. A display box comprising a base and a cover fitted thereover, the cover being cut or scored to 40 provide two hinged portions bent downwardly between the lateral walls of the cover into positions slanted toward each other and into an inclined relationship to the plane of the top of the cover where they form a stable support for the base

in an inclined position with one of said portions bearing against and supporting one end of the base and the other bearing against and supporting the bottom of the base.

2. A box according to preceding claim 1, in which one of said inclined portions includes a tongue and the other is provided with a notch into which said tongue extends prior to bending said portions into the inclined positions above described. 10

3. A box according to preceding claim 1, in which both of said portions form parts of the top of the cover.

4. A box according to preceding claim 1, in which one of said portions forms a part of the 15 top of the cover and the other a part of a lateral wall of the cover.

5. A box according to preceding claim 1, in which a lip forming part of the material of the cover is adapted to project over the upper edge 20 of that end of said base which is supported on one of said inclined portions.

6. A box according to preceding claim 1, in which both said inclined portions form parts of the top of the cover and one of them has a part 25 extending under the edge of said base which lies between said end and said bottom.

7. A box according to preceding claim 1, in which the angle of inclination which said portions assume depends upon the depth of the cover. 30

8. A display box comprising a base and a cover fitted thereover, the top portion of the cover being provided with two scored lines adapted to function as hinges, one adjacent one end and the other adjacent the other end, the intermediate 35 portion of the cover being provided with transverse lines of severance, the distance between the two lines being, with respect to the linear dimensions of the body part, such as to constitute a stable support for the bottom of the box in 40 inclined relationship to the plane of said top portion.

JOHN T. HARTNETT.
